UNITED STATES PATENT OFFICE

JOSEPH T. HORN, OF NEWARK, NEW JERSEY

TRAFFIC SIGN STAND

Application filed June 11, 1929. Serial No. 370,073.

This invention relates to portable stands for use in the streets for supporting traffic signs, lanterns, or the like, or for indicating barriers or boundaries for traffic. Such stands are generally made with heavy bases of circular form so that they can, while not offering an immovable obstacle to traffic, still be ruggedly supported and at the same time easily moved by rolling them on the circular edge of their bases. The stands have in general a circular base, a tubular upright stanchion secured in the base, and a sign mounted on top of the upright. Heretofore the uprights have been screw threaded into the base, but this means has proven quite inadequate, as the rough treatment the stand gets soon breaks the upright at the point where it enters the base.

My invention relates to means for making the joint between the upright stanchion and the base more substantial, and it comprises a special construction of conical base socket and cone shaped wedges fitted therein, between which the upright is securely clamped. In this way a firmer grip is maintained on the pipe and screw threads with their attendant weakening effect are avoided. This and further details of my improved street sign will appear from a detailed description of an embodiment of the invention as shown in the accompanying drawings, in which

Figure 1 is a front elevation of a traffic sign stand.

Figure 2 is a side view of the sign.

Figure 3 is a vertical axial section through the base.

Figure 4 is a side view of a holding wedge.

Figure 5 is a view looking up under the base.

The base or standard 1 is preferably made of an integral piece of metal and in the embodiment shown comprises a circular flange or tread 2 adapting it to be rolled as a wheel when the stand is tipped; an upwardly-presented conoidal body 3; and an inverted frusto-conical socket 4 which depends within the hollow body 3 and is provided at the bottom with two oppositely-arranged flanges 5 which form between them opposite radial slots 6. The bottom flanges 5 are provided

with part-circular notches 5a adapted to receive and slidably engage the vertical pipe or stanchion 7. Slidable on the stanchion 7 is a wedging device which is preferably constructed in two hollow semi-frusto-conical portions 8 provided with axially and peripherally-spaced bosses 9 which are adapted to bear against the inner walls of the conical socket 4. As shown in Figures 3 and 4, each of the wedge-portions 8 is provided with a radial slot of T-shaped cross-section for the reception of a bolt 10, said bolts being also arranged in the slots 6 between the flanges 5 at the bottom of socket 4 so that when the nuts on said bolts are tightened up, the wedge-portions 8 will be drawn into interlocking engagement with the stanchion 7 and socket 4 and thus serve to rigidly unite these parts in any position the stanchion may be adjusted to in respect to the base 1. Said T-slots comprise relatively broad upper portions 12 extending entirely through the wedge portions for accommodating the heads of the bolts and relatively narrow lower portions 13 for the shanks of said bolts, the narrow portions 13 being closed at their inner ends to provide bearings 11 which engage the central stanchion 7. A flange 14 on the upper part of each of the wedges 8 provides an extended bearing surface against the stanchion. The stanchion 7 at its upper end has clamped to it a bifurcated arm 15 of a sign 16, the bifurcations being clamped to the stanchion 7 by bolts 17. As shown, I prefer to make the sign with tapering flanges around its edge, as shown at 18, terminating in a ball 19 at the top which is used as a pivot in the palm of the hand when lowering the sign on its base 1. At 20 are shown ring shaped ears for supporting lanterns, and at 21 is an orifice for the passage of a rope when the sign is being used for a post for a guard line.

It will be seen that the stanchion may be an ordinary piece of plain pipe without threads and that instead of being weakened where it passes into the base, as would be the case if it were screw-threaded, it is actually reinforced and made stronger at this

point. It will be also seen that, owing to the upper and lower contacts that the wedges make both with the pipe and with the socket, the former is held there rigidly in its vertical position.

5 I claim:—

1. In a traffic sign stand, the combination comprising a base plate having a central conical socket, a sign supporting stanchion located centrally in said socket, and wedges in the socket holding the stanchion securely in its central position, said base and said wedges having flanges and bolts passing through orifices in said flanges whereby the 10 wedges may be drawn into the socket and grip the stanchion.

2. In a traffic sign stand, the combination comprising a base plate having a central conical socket, a sign supporting stanchion located centrally in said socket, and wedges in the socket holding the stanchion securely in its central position, said base having a slotted flange at the base of the socket and said wedges having slotted flanges at their lower ends with bolts passing through the said slots to form a means of drawing the wedges downward to form a clamping grip for the stanchion.

3. In a traffic sign stand, the combination comprising a base having a central tapered socket, a sign stanchion movable through said central tapered socket, a tapered wedge movable along said sign stanchion and adapted to interlock with said sign stanchion 35 and tapered socket in different relative positions of the former with respect to the latter, and means interengaging between said base and tapered wedge for drawing said wedge into interlocking engagement with said sign stanchion and socket.

4. In a traffic sign stand, the combination comprising a circular base, an upwardly contracted conoidal extension, a downwardly-tapered conical socket depending within said 45 conoidal extention from the upper end thereof, a stanchion extending through said socket, and a conical wedge for locking said stanchion to said socket, and an adjustable connection interacting between said conical wedge and the bottom end of said socket for tightening said conical wedge.

5. In a traffic sign stand, the combination of a base provided with an upwardly-contracted extension and a downwardly-contracted socket depending from the upper edge of said extension, a stanchion having its lower end presented within said socket, a wedge slidable along said stanchion and adapted by its wedging action to form an 55 interlocking member between said stanchion and the inner wall of said socket, and adjustable means interengaging between said wedge and socket for drawing the former into the latter.

6. In a traffic sign stand, the combination

of a base having a centrally disposed raised portion provided with a downwardly-tapered socket, a stanchion having its lower end disposed within said tapered socket, a wedge movable into interlocking engagement with the inner wall of said tapered socket and the outer wall of said stanchion, and means interacting between said wedge and said socket for tightening said wedge in its interlocking position.

7. In a stand for traffic signs, the combination with a sign-supporting stanchion, of a standard provided with a circular flange or tread and having a downwardly-contracted socket with a bottom wall provided with a central opening for permitting the axial adjustment of said stanchion, wedge-portions having their outer walls slidably engaging the downwardly-contracted inner wall of said socket and adapted by the wedging action of said inner wall of the socket to be clamped to said stanchion, and adjustable connections between said wedge-portions and the bottom wall of said socket for drawing said wedge-portions downwardly into said socket and into clamping engagement with said stanchion in any position to which it may be adjusted.

8. In a stand for traffic signs, the combination with a sign-supporting stanchion, of an integral hollow shell comprising a circular flange or tread, an upwardly-presented conoidal body and a depending inverted frustoconical socket having a bottom wall provided with a central opening through which said stanchion is axially adjustable and with radial slots extending away from said central opening, frustoconical wedge portions provided with peripheral bearing surfaces and adapted to be clamped to said stanchion by their wedging engagement with the inner wall of said frustoconical socket, said frustoconical wedge portions being provided with radial slots and bolts extending through the first and second-mentioned radial slots for drawing said wedge portions into clamping engagement with the stanchion.

9. In a stand for traffic signs, the combination with a sign-supporting stanchion, of an integral hollow base comprising a circular flange or tread, an upwardly-presented conoidal body and a depending inverted frustoconical socket provided at the bottom with oppositely-arranged transverse flanges adapted to slidably engage said stanchion and forming between them oppositely extending radial slots, and means for rigidly supporting said stanchion within said inverted frustoconical socket, said supporting means comprising two hollow semi-frustoconical wedge portions provided with axially-spaced bearing surfaces adapted to be clamped on to said stanchion and with axially and peripherally-spaced bearing

bosses adapted to engage the inner wall of said frustoconical socket, said frustoconical wedge portions being provided with radial slots and bolts mounted in radial T-shaped slots and extending through the radial slots in said wedge-portions and bottom wall of said frustoconical socket.

5 10. In a traffic sign stand, the combination comprising a base, a stanchion, a socket in the base adapted to receive the stanchion, a clamping wedge in the socket, and a member operating on said base against said clamping wedge to press the clamping wedge against the stanchion to hold it securely in 15 place.

11. In a traffic signal stand, the combination of a base, a stanchion, an adjustable part movable into and out of interlocking position with respect to said base and stanchion, and means engaging said base for 20 adjusting said adjustable part.

12. In a traffic signal stand, the combination of a base, a movable stanchion, relatively adjustable parts adapted to form an 25 interlock between said base and stanchion, and means interengaging between said base and said relatively adjustable parts for adjusting said parts relatively to each other for rigidly uniting said stanchion to said 30 base.

13. In a traffic signal stand, the combination of a base, an adjustable stanchion, adjustable wedges adapted to form a rigid 35 interlock between said base and stanchion, and means for adjusting said wedges relatively to said base and stanchion for interlocking said wedges therewith.

14. In a traffic sign stand, the combination comprising a base having a tapered socket, a stanchion adjustable endwise with respect 40 to the axis of said socket, a wedge movable into interlocking engagement with said stanchion and socket in different relative positions of said stanchion with respect to said socket, and means interacting between said wedge and socket for tightening said wedge in its interlocking position.

15. In a traffic sign stand, the combination comprising a base member provided with a 45 socket, a stanchion member adapted to be inserted into said socket, a clamping piece in the socket, and means interacting between said clamping piece and one of said members to press the clamping piece against 55 the stanchion member.
